UNITED STATES PATENT OFFICE.

JAMES H. ROSENTHAL, OF CHISELHURST, ENGLAND, ASSIGNOR TO THE BABCOCK & WILCOX COMPANY, OF BAYONNE, NEW JERSEY, A CORPORATION OF NEW JERSEY.

STEAM-GENERATOR.

1,132,036.

Specification of Letters Patent. Patented Mar. 16, 1915.

Application filed April 10, 1913, Serial No. 760,129. Renewed December 26, 1914. Serial No. 879,230.

To all whom it may concern:

Be it known that I, JAMES H. ROSENTHAL, a subject of the King of Great Britain, residing at Kemnal Manor, Kemnal Road, 5 Chiselhurst, Kent, England, have invented certain new and useful Improvements in Steam-Generators, of which the following is a specification.

This invention relates to water tube steam generators in which the steam generating tubes are arranged at a steep angle, and the front or main bank arranged in sections composed of tubes connected at their ends to headers of any well-known type.

15 The invention will be understood by reference to the accompanying drawings in which—

Figure 1 is a vertical section of a boiler showing one embodiment of my invention; 20 Fig. 2, a similar view of a modified form of tube and tube connections which may be employed in one of the banks of tubes; and Fig. 3 a similar view showing another modification of tube connection.

25 Similar reference numerals indicate similar parts in the several views.

Referring to Fig. 1 the numeral 1 designates the front wall of the boiler setting; 1' the rear wall; 2 the furnace; and 3 a 30 bank of generating tubes inclined upwardly at a steep angle toward the front wall of the setting and extending substantially from the bridge wall 4 to the roof of the setting. These tubes are arranged in sections and are 35 expanded at their lower and upper ends into headers 5 and 6, respectively, of any well-known type. These headers are provided with hand-hole fittings 7 located opposite the ends of each of the tubes to facilitate 40 cleaning and renewal. The lower headers 5 are connected by nipples, or short tube lengths, to a water drum 8, and the upper headers 6 are connected by tubes 9 with a steam and water drum 10, the ends of the 45 tubes 9 being exposed above the water line and terminating in a steam drying device 11. The drums 8 and 10 are connected by a bank of downcomer tubes 12 disposed at a greater angle of inclination to the horizontal than 50 are the tubes of the bank 3.

In the triangular space between banks 3 and 12 a sectional superheater 13, of a well-known type, is located. In the upper part of the space between the bank 12 and the 55 rear wall of the setting is located an econo-

mizer comprising tubes 14 connected to cross boxes 15 and 16, the former having a suitable cold water inlet and the latter a hot water outlet.

Suitable baffling may be introduced to 60 direct the course of the gases from furnace 2. As shown, a baffle 17 rests upon the front row of the tubes of bank 3 and extends upwardly from the lower headers 5 substantially half-way of the length of the bank. 65 From baffle 17 extends a cross baffle 18 to direct the gases across the uptake ends of the tubes of said bank. The tubes of the front row of the second or rear bank are enclosed with tiles 19 extending downwardly 70 from the steam and water drum to a baffle 20 extending across the triangular space between the two banks of tubes. The back row of tubes of the bank 12 support a longitudinal baffle 21 extending upwardly from the 75 water drum 8, so that after the gases leave the superheater space they are directed downwardly among the tubes of the main bank and then upwardly among the tubes of the rear bank, and finally across the econo- 80 mizer to the outlet 22. A wall 23 extending from the floor up to the water drum 8 prevents the gases escaping below said drum.

The water from the economizer is led to drum 10 through a suitable connection, 85 passes down the tubes 12 into drum 8, thence into the headers 5 in an upward direction through the tubes of bank 3, and thence by the connections 19 into the steam drying space disposed above the water line in 90 drum 10.

In lieu of using straight tubes with embossed tube sheets, as shown in Fig. 1, I may adopt the construction shown in Fig. 2, wherein the tubes of the second or rear bank 95 are bent radially at their upper and lower ends, so dispensing with the embossed tube sheets.

An alternative construction is shown in Fig. 3 in which the water drum 8 is disposed with and its part in the working of the boiler taken by an extension 5' of the headers 5, hand-hole fittings 7' being provided opposite each of the tubes of the bank 12. In this last arrangement the tubes of 105 the bank 12 are straight at their lower ends and can be either bent or straight at their upper ends depending upon whether an embossed tube sheet is or is not used for the drum 10.

What I claim and desire to secure by Letters Patent of the United States is:—

1. A water tube boiler comprising a furnace having a bridge wall, a bank of generating tubes inclined forwardly and extending from the bridge wall to the roof of the setting, headers into which said tubes are expanded, a steam and water drum connected to the upper headers, a water drum connected to the lower headers, a second bank of tubes connecting said drums, and baffles to direct the gases across and among the tubes.
2. A water tube boiler comprising a furnace having a bridge wall, a bank of generating tubes inclined forwardly and extending from the bridge wall to the roof of the setting, headers into which said tubes are expanded, a steam and water drum connected to the upper headers, a water drum connected to the lower headers, a second bank of tubes connecting said drums, and baffles to direct the gases across and among the tubes, said second bank being at a greater angle to the horizontal than the tubes of the first named bank.
3. A water tube boiler comprising a furnace having a bridge wall, a bank of generating tubes inclined forwardly and extending from the bridge wall to the roof of the setting, headers into which said tubes are expanded, a steam and water drum con-

nected to the upper headers, a water drum connected to the lower headers, a second bank of tubes connecting said drums, baffles to direct the gases across and among the tubes, an economizer in the upper part of the space at the rear of the second bank of tubes, and an outlet for the gases in the rear wall of the setting whereby the gases are directed across the economizer on their way to the stack.

4. A water tube boiler comprising a bank of main generating tubes inclined upwardly toward the front of the setting, headers into which said tubes are expanded, a steam and water drum connected to the upper headers, a water drum connected to the lower headers, a second bank of tubes connecting said drums, baffles to direct the gases upwardly and then across the uptake ends of the main bank of tubes, a baffle on the front row of the rear bank of tubes extending downwardly from the steam and water drum, and a baffle on the rear bank of tubes extending upwardly from said water drum.

In testimony whereof I hereunto sign my name in the presence of two subscribing witnesses.

JAMES H. ROSENTHAL.
